UNITED STATES PATENT OFFICE.

EZEKIEL C. CONDIT, OF KANSAS CITY, MISSOURI.

FURNACE.

SPECIFICATION forming part of Letters Patent No. 397,697, dated February 12, 1889.

Application filed May 22, 1888. Serial No. 274,872. (No model.)

To all whom it may concern:

Be it known that I, EZEKIEL C. CONDIT, of Kansas City, in the county of Jackson and State of Missouri, have invented certain new and useful Improvements in Furnaces, of which the following is a specification.

My invention relates to furnaces for warming buildings; and the invention consists in a novel construction of the furnace, whereby its capacity can be adapted to the varying conditions of the weather, as hereinafter more fully set forth.

Figure 1 is a side elevation with a portion shown in section on the line *xx* of Fig. 2. Fig. 2 is a horizontal sectional view on the line *yy* of Fig. 1.

The object of this invention is to produce a furnace for heating buildings that will enable the amount of surface heated to be varied as circumstances may require, and that can be drawn bodily out of the hot-air chamber when necessary for cleaning or repair.

To construct my improved furnace, I make an oblong body, *A*, which may be oval in form, as represented in Fig. 2, this part being preferably of wrought-iron, with the top and bottom plates of cast-iron. It has at the front a fire-box, *F*, and ash-pit *P*, set below the body, as shown in Fig. 1. In rear of the grate, and on a line with its outer edge on each side, I locate an oblong air-pipe, *h*, which extend from the rear end of the grate to near the rear end of the body *A*, as shown in Fig. 2, thereby dividing the body into three chambers or passages in rear of the grate, these pipes *h* being open at top and bottom, so that the air can pass through them. Along each side, between these pipes *h*, I locate one or more rows of vertical air-tubes, *d*, and between the pipes *h*, I locate another but shorter row of air-tubes, *i*, all as shown in Fig. 2. At the front the space between the two oblong pipes *h* is provided with a valve or damper, *l*, by which said space or passage can be opened or closed at will, and at the rear ends of these pipes *h*, I arrange two other dampers, *k* and *k'*, as shown in Fig. 2. These dampers are each provided with journals on which they turn, their lower journals projecting through the bottom plate, and having arms *e* attached, as shown in Fig. 1 and in dotted lines in Fig. 2, to which rods *g*

g and *g'* are connected, so they can be operated from front, as shown. If preferred, the front valve can have its operating arm and rod located at the top, as indicated in Fig. 1; 55 but as the ash-box is considerably narrower than the body there is room for it to pass alongside of the fire-box at the bottom, it being immaterial whether the rods be located at top or bottom.

The smoke-pipe *S*, I connect to the furnace at or near its center, as shown in Fig. 1, and to enable it to be readily disconnected from the furnace while held fast in the brick-work above I make use of a hinged collar, *m*. (Shown 65 in section in the detached figure.) This collar, being provided with a hinged joint, *w*, at one side, can be readily put around the end of the pipe and the short collar *e*, which projects from the top of the furnace, and then be 70 drawn up tight by bolts passing through its flanges on the side opposite the joint, as shown in Fig. 1 and in the detached figure. In order to make the joint gas and smoke tight, I wrap a sheet of asbestos packing around the 75 collar and pipe before applying the collar, as shown in detached portion of Fig. 1.

As shown in Fig. 1, I mount the furnace on wheels *c*, the rear portion being provided with legs *I*, on account of its greater height, these 80 wheels being grooved, so as to run on rails *b*, laid in the bottom of the hot-air chamber, as shown. The furnace is to be inclosed in a brick chamber composed of walls at each side and at the rear end, but open at front, as shown 85 in Fig. 2, it having a top, *B'*, composed of brick-work supported on metal bars *a* in the usual manner, this top being built tight around the smoke-pipe *S* to prevent the escape of the hot air and hold the pipe securely 90 in place.

To the front of the furnace is secured a cast-iron plate, *D*, of the proper size to completely close the open end of the air-chamber, when the furnace is shoved therein to its position; 95 and in order to insure this plate fitting snugly to the wall the rails *b* are slightly inclined to the rear, so there will be a tendency of the furnace to run inward and thus draw the plate *D* tight against the brick walls at the front. 100 If there be any appreciable opening left at any point between this plate *D* and the wall,

it will be closed by mortar when the furnace is prepared for use in the fall.

The results of this construction are as follows: By closing the dampers k and k' at the rear and opening the front damper, l , it will be seen that only a small portion of the furnace will be heated, as the products of combustion will pass direct from the grate into the space between the oblong pipes h , and thence direct to the smoke-pipe S , thus adapting the furnace to very mild weather, when the minimum of heat is required. When more heat is required, by closing the valve l and either k or k' the flame and smoke will pass along one side between the oblong pipe h and the wall of the furnace-body on that side, thence through the open valve-space at the rear, and then forward between the oblong pipes h to the smoke-pipe S , and of course heating the tubes d on the side along which it passes, and also the tubes i and one of the pipes h on one side its whole length, and both of them on their inner side part way. For extreme cold weather the valve l will be closed, and both valves k and k' opened, in which case the smoke and flame or heat will divide at the front and pass along both sides, then unite at the rear and enter between the oblong pipes h , thus heating all parts of the furnace, the body A , and the pipes d , h , and i . By these means the heating capacity of the furnace can be varied to suit all conditions of weather by merely opening and closing the valves.

When it is desired to get at the furnace for cleaning it or for repairs, it is only necessary to remove the collar m , so as to detach it from the smoke-pipe, and which can readily be done through a man-hole in one of the side walls, as shown by dotted lines, Figs. 1 and 2, and which is closed by a hinged door set when the heat-chamber is built, and then draw the furnace forward out of the chamber, where it can be got at. The removability of the fur-

nace enables the smoke-pipe to be cleaned without removing it, and also enables the heat-chamber to be cleaned out, and all dust and articles which get into it by accident or otherwise to be removed, whenever necessary. 45

The importance of this will be the more readily understood when it is stated that not infrequently dead rats, cats, &c., have got into the heat chambers or flues and necessitated the tearing down of the brick-work to get at them for removal. By my improvement all this trouble and delay are obviated, as the furnace can be removed with but a few moments' work and the brick-work left intact. The advantages of these improvements are too obvious to require further mention. 55

Having now fully described my invention, 60 what I claim is—

1. A furnace consisting of the body A , having the two oblong air-pipes h arranged therein in rear of the fire-box, and the dampers l and k , located as shown, for the purpose of directing the products of combustion and thereby heating more or less of the furnace, as herein set forth. 65

2. The combination, in a heating-furnace, of the body A , the oblong air-pipes h , with the two exterior rows of air-tubes, d , and the valves k , k' , and l , all arranged substantially as shown and described. 70

3. The combination, in a furnace, of the body A , having the oblong air-pipes h , the two rows of air-tubes d , and the central air-tubes, i , located therein as shown, with the valves k , k' , and l , all arranged to operate as set forth. 75

In witness whereof I hereunto set my hand 80 in the presence of two witnesses.

EZEKIEL C. CONDIT.
